CLAIM

The ornamental design for a hitch mountable vehicle protector, as shown and described.

DESCRIPTION

FIG. 1 is a perspective view of a first embodiment of the hitch mountable vehicle protector showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and
FIG. 7 is a bottom plan view thereof.

FIG. 8 is a perspective view of a second embodiment of the hitch mountable vehicle protector showing our new design;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof; and,
FIG. 14 is a bottom plan view thereof.
